UNITED STATES PATENT OFFICE.

HENRY J. AVERBECK, OF COVINGTON, KENTUCKY.

AUTOMATIC FEED-REGULATOR.

SPECIFICATION forming part of Letters Patent No. 786,942, dated April 11, 1905.

Application filed June 10, 1904. Serial No. 211,959.

To all whom it may concern:

Be it known that I, HENRY J. AVERBECK, a citizen of the United States of America, and a resident of Covington, county of Kenton, 5 State of Kentucky, have invented certain new and useful Improvements in Automatic Feed-Regulators, of which the following is a specification.

My invention relates to cutting-machines in 10 which a table for holding the work is reciprocated beneath the cutting-tool, and is especially adapted to the class known as "shapers." Its object is to provide a means for stopping automatically the movement of the table at 15 any predetermined point. This object is attained by means described in the specification and illustrated in the drawings, in which—

Figure 1 is a side elevation of a shaper provided with the automatic feed-regulator embodying my invention. Fig. 2 is a vertical sectional view through the apron and ways upon which it works, showing the attachment embodying my invention in detail. Fig. 3 is a detail top plan view of the ways upon which 25 the table reciprocates. Fig. 4 is a detail sectional view, upon an enlarged scale, of the adjustable contact-block. Fig. 5 is a front elevation of the ways with the apron removed therefrom to expose the feed-screw and the 30 regulating-rod. Fig. 6 is a detail sectional view of the cam upon the end of the feed-regulating rod. Fig. 7 is a sectional view, upon a much-enlarged scale, of the pawl for engaging the ratchet-wheel upon the feed-screw and 35 the reciprocating pin which contacts the same. Fig. 8 is a perspective view of the reciprocating pin shown in Fig. 7. Fig. 9 is a sectional view of the regulating-rod, taken upon line $x-x$ of Fig. 5. Fig. 10 is a detail view of the 40 bracket which is to be secured to the apron to carry the reciprocating block along the regulating-rod.

Referring to the parts, in the drawings I have illustrated my invention as applied to a 45 shape of ordinary construction and will give a brief description of the same.

The apron A is fed along the ways B by means of a feed-screw C. The feed-screw has upon its end a ratchet-wheel c and a loose

sleeve c', which carries a pawl c², which engages the teeth of the ratchet-wheel, the tooth c³ of the pawl being formed with a straight and a cam-shaped edge in the usual manner, so that it will engage the teeth of the ratchet in moving in one direction and will pass over them in moving in the opposite direction, so as to impart an intermittent rotation to the feed-screw from the driving-shaft D, upon which is an eccentric d, which is coupled by an arm c⁴ with the sleeve c'.

60

My invention consists in providing a means of raising the pawl c² out of contact with the ratchet-wheel c at a predetermined point of travel in the apron. In carrying out this object I mount a regulating-rod E rotatably in 65 the ways B, parallel to the feed-screw C, and upon its end I mount a cam b, which carries a roller b' for contacting the loose pin c⁵, which is mounted in the end of the sleeve c' and has formed in it an oblong ring c⁶ to fit 70 over the end of the shaft C to permit of its having a vertical motion thereon. The upper end of the pin c⁵ contacts the lower end of the pawl c², which is mounted reciprocally in the vertical sleeve c⁷. Pawl c⁵ has two 75 V-shaped grooves c⁸ c⁹ formed in it, which are to be engaged by the pointed ends of studs c¹⁰ c¹¹, which project in through perforations in the walls of the sleeve c⁷, in which they are held by flat springs c¹² c¹³. The 80 groove c⁹ is made at a point in the pawl such that when it is engaged snugly by the points of the studs c¹⁰ c¹¹ the tooth c³ engages one of the teeth of the ratchet firmly, the springs allowing the point of the studs c¹⁰ c¹¹ to have 85 enough play in the groove c⁹ to allow the tooth c³ to be raised out of contact with the ratchet-teeth in getting a new bite. When the pin c⁵ is raised upon the rotation of the rod E by the roller b', the pawl is carried upward, so that the studs c¹⁰ c¹¹ pass into the groove c⁸ and hold the tooth c³ out of contact with the ratchet-wheel, so that the sleeve reciprocates upon the feed-screw without moving the same.

90

The tripping mechanism, by which the regulating-shaft E is actuated at a predetermined point to cut off the feed, is as follows: Secured

95

to the ways B is a horizontal guide-bar F, upon which is mounted a sliding contact device f. The contact device consists of a split block, consisting of an upper half f¹ and a lower half f², which are held together by a clamping-screw f³, by loosening which the block may be adjusted to any point upon the guide-rod F. The front faces of the parts f¹ f² are recessed to receive the roller f⁴, which is of smaller depth than the recess and is held upon the sliding pin f⁵, which passes down through perforations in the block and the roller f⁴ and is normally held upward by a spring f⁶. Upon the adjustable rod E is splined a sliding block e, which is moved along the rod E by means of a bracket a, which is secured to the inner side of the apron A and has lugs a' and a'' for straddling the block e. In alignment with the point at which the bracket a is secured to the apron it has a vertical channel a³, and registering with the channel a³ is a horizontal channel a⁴. Within channel a³ a loose rod G is placed so as to rest upon the block e, and within channel a⁴ is a second sliding rod G', which projects rearwardly from the apron a short distance at the same horizontal level as that of the normal position of the roller f⁴. The ends of the rods G and G' where they contact each other are made tapering, preferably at a taper of forty-five degrees. It is apparent that the contact device f may be put at a point upon the guide-rod F such as to contact the rod G' at any desired point in the travel of the apron. When it so contacts the rod G', it pushes the same inward, which causes the rod G to be pushed downward and to impart a slight rotation to the shaft E. While the rods G G' and the contact device might be made of a character such that this rotation would be of sufficient magnitude to throw the pawl upward, so that the studs c¹⁰ c¹¹ engage the groove c⁸, it has been found expedient to make the parts aforesaid of a size such that this rotation would be slight and to provide a means for increasing the rotation. This is done in the following manner: Upon the shaft E is a fixed cam e', which projects inward and has upon its inward end a point e'', beneath which is a cam-shaped face e³. Adjacent to the point e'' and mounted in the ways B is a spring-pressed pin H, which is pointed upon its end h. In their normal positions the point h stands just above the point e'', as shown in Fig. 9, and has no tendency to rotate the shaft E, since it is held against rotation in a direction downward by means of a small lug a⁵ upon the bracket, as shown in Fig. 2, or in any other suitable manner. As soon as the point e'' is carried up above the point h by the downward push of the rod G the spring h' causes the point h to travel along the cam e³, and thereby impart sufficient rotation to the shaft E to bring the roller b' into positive contact with the pin c⁵ and to raise the pawl c² up, so that the pins c¹⁰ c¹¹

snap into the groove c⁸. It is then seen that the tooth c³ being out of engagement with the ratchet the feed is cut off.

I have secured a small arm n upon the end of the shaft E, which strikes a bell N, which is secured to the ways B, to notify the operator when the feed has been cut off.

In operation it is seen that when the operator desires to have a certain length of cut made upon the work he adjusts the contact device at a point he desires the feed to be cut off, and then he need not pay any further attention to the machine, but that when in the travel of the apron the rod G' reaches the contact device the roller f⁴ will strike it and push the rod G downward, thereby rotating the shaft E and throwing the pawl c² out of contact with the teeth of the ratchet c, and thereby stop the movement of the apron. The ringing of the bell will tell the operator when the cut-off has worked. Roller f⁴ is made capable of receiving a vertical adjustment, so that by pressing it downward it may allow the rod G' to pass it. A number of contact devices similar to device f may be secured upon the guide-rod F, so that a number of cuts may be made upon the same piece of work without readjustment of the parts. In order that the feed may be cut off when the apron has reached the limit of its travel in either direction, I have placed stationary pins b² b³ upon the way B to strike the block e and cut off the feed.

What I claim is—

1. The combination of ways, an apron to be reciprocated upon the ways, a feed-screw for reciprocating the apron, a driving-shaft, means for coupling the feed-screw and the driving-shaft, a rotatable feed-regulating shaft journaled adjacent to the feed-screw, a device carried by the regulating-shaft for breaking the connection between the feed-screw and the driving-shaft, a second device carried by the apron for rotating the regulating-shaft, and an adjustable contact device adjacent to the apron for actuating the second device to cut off the feed at a predetermined point.

2. The combination of ways, an apron to be reciprocated upon the ways, a feed-screw for reciprocating the apron, a driving-shaft, a loose sleeve upon the feed-screw, a ratchet secured to the feed-screw, a pawl carried by the sleeve to engage the ratchet, a feed-regulating shaft, a cam carried by the regulating-shaft for contacting the pawl and carrying it out of engagement with the ratchet, a device carried by the apron for imparting a rotatory motion to the regulating-shaft and a contact device mounted adjacent to the path of travel of the apron for actuating said device to cut off the feed at a predetermined point.

3. The combination of ways, an apron reciprocating upon the ways, a feed-screw for reciprocating the apron, a driving-shaft, means for coupling the driving-shaft and the feed-

screw, a feed-regulating shaft mounted adjacent to the feed-screw, a device carried by the regulating-shaft for breaking the connection between the feed-screw and the driving-shaft, 5 a sliding block mounted reciprocally upon the regulating-shaft and coupled to the apron, a contact device mounted adjustably relatively to the path of the apron, and movable rods mounted in the apron contacting the sliding block and having one end projecting into the path of the contact device.

4. The combination of ways, an apron reciprocating upon the ways, a feed-shaft, a driving-shaft, a loose sleeve and a fixed ratchet mounted upon the feed-shaft, a rod for connecting

the sleeve and the driving-shaft, a pawl mounted movably in the sleeve adapted to contact the ratchet and having two adjacent grooves cut into it, a stud, or studs mounted in the sleeve to engage one or the other of the grooves, 20 a spring, or springs for engaging the stud, or studs to hold them in engagement with the pawl, a tripping device carried by the apron to contact the pawl at a predetermined point and raise it up and carry the stud or studs into 25 the lower of the grooves to cut off the feed.
